UNITED STATES PATENT OFFICE.

FERDINAND G. HAAS, OF ST. PAUL, MINNESOTA.

PISTON.

1,332,213.

Specification of Letters Patent.

Patented Mar. 2, 1920.

Application filed May 24, 1916. Serial No. 99,542.

To all whom it may concern:

Be it known that I, FERDINAND G. HAAS, a citizen of the United States, residing at St. Paul, in the county of Ramsey and State of Minnesota, have invented new and useful Improvements in Pistons, of which the following is a specification.

My invention relates to improvements in pistons of the class illustrated and described in Letters Patent No. 1,092,834, issued to me April 14, 1914, in which is disclosed a piston comprising a head, a plurality of peripheral sleeves slidable longitudinally on the head, resilient packing rings between the ends of the sleeves, and compression members to shift the sleeves and thereby expand said rings radially.

It is the object of my present invention to simplify pistons of this type, to reduce the weight thereof, preserve durability and promote efficiency.

A further object is to protect certain novel features of construction hereinafter described and pointed out in my claims.

In the drawings, Figure 1 is a central longitudinal sectional view of my improved piston; Fig. 2 is a transverse sectional view taken on the line 2—2 of Fig. 1; and Fig. 3 is a plan of said piston.

Referring to the drawings, my piston comprises generally a head A, consisting of a hollow cylindrical core 11 having an end 12 and a peripheral shoulder 13 at one extremity, and piston sleeves 14 and 15. Opposed segments are cut away from the annular wall of the core 11, between the ends thereof, to lighten the piston and for another purpose hereinafter described. The upper end of the core provides an annulus or bearing 16 for one end of the sleeve 14 and the lower end of said core provides a similar annulus or bearing 17 for the other end of said sleeve and also for one end of the second sleeve 15. Bosses 18 are formed

within the core 11 to receive a wrist-pin 19, and said core 11 and bosses 18 are reinforced by ribs 20, 21 and 22. The piston sleeves 14 and 15 are slidable longitudinally upon the core 11 and fit snugly thereon. As shown, I have provided upon the inner peripheries of said piston sleeves 14 and 15 a number of annular and longitudinal reinforcing ribs. One rib 23 is formed at each end of each sleeve, and a similar rib 24 near the middle thereof, while longitudinal ribs 25 are spaced at intervals

between said annular ribs 23 and 24. The sleeve 14 is placed upon the core 11, one end bearing upon the annulus 16 and the other end on the annulus 17. A resilient packing ring 26 is placed around said annulus and between the piston sleeve 14 and flange 13. The sleeve 15 is placed upon the core 11, one end thereof encircling the annulus 17, and a second resilient packing ring 27 is inserted between the adjacent ends of the sleeves 14 and 15. Said sleeves may be shifted longitudinally upon the core by compression devices to be presently described, to expand the resilient packing rings radially against the walls of a cylinder. To facilitate in this expansion of the rings, I have beveled the ends of the sleeves 14 and 15 and the lower side of the flange 13, as clearly illustrated in Fig. 1. The sleeve 15 is furnished at its lower end with horizontal flanges 28 which are enlargements of the lower rib 23. The compression devices are bolts 30. These bolts, threaded at their ends in the bosses 18 and passing through the wrist-pin 19 in said bosses, also pass through perforations 29 in said flanges 28. Nuts 31 and 32 upon each bolt are arranged at opposite sides of the flange 28 through which said bolt passes. Said nuts 31 are employed to secure the piston sleeves 14 and 15 upon the core 11 and to shift said sleeves and the nuts 32 serve as locks to prevent the loosening of said first nuts.

It will be noticed, that in addition to shifting and securing the sleeves 14 and 15 upon the core 11, said bolts 30 secure the wrist-pin 19 against movement in the bosses 18 and further hold the lower end of the sleeve 15 in alignment.

The piston sleeve 14 is perforated in a number of places to form lubricating ducts 33. These ducts open within said sleeve at the upper edge of the intermediate annular rib 24 and oil accumulating upon said ribs 100 is conducted through these perforations to the oil groove 34 adjacent to the wall of the cylinder surrounding the piston. The openings in the core 11 formed by removing segments from its annular wall, as above described, are so proportioned that they communicate with the oil ducts 33 in all adjustments of the sleeve 14, thus permitting the unobstructed passage of vaporized lubricant and the splash of oil to the oil ducts 33.

The resilient packing rings should be formed of a composition adapted to resist

heat and wear and contain no lubricant. Such material as asbestos and ground fiber is preferred, or asbestos alone may be employed, but applicant does not limit himself 5 to any particular fibrous material or composition.

Having described my invention, what I claim as new and desire to protect by Letters Patent, is:

- 10 1. In a piston, a hollow cylindrical core having openings in its annular wall between the ends thereof, a plurality of peripheral sleeves slidable on said core, resilient packing rings encircling the core and adapted to be compressed between said sleeves, devices to shift and secure the sleeves upon said core, one of said sleeves being formed with oil ducts in its annular wall communicating with the openings in said core in all positions of adjustment of said sleeve.
- 15 2. In a piston, a hollow cylindrical core having a peripheral flange thereon, bosses within the core, a wrist-pin mounted at its ends in said bosses, a peripheral sleeve slidably mounted upon said core, a resilient packing ring between said flange and the adjacent end of said sleeve, a second peripheral sleeve slidably mounted at one end on said core, a second resilient packing ring between the adjacent ends of said sleeves, bolts secured in said bosses and passing through said wrist-pin and nuts on said bolts coöperating with said second sleeve to shift said sleeves and expand said rings radially, said bolts being also adapted to form bearings on the otherwise unsupported end of said second sleeve.
- 20 3. In a piston, a hollow cylindrical core having openings in its annular wall between the ends thereof, a plurality of peripheral sleeves slidable on said core, resilient packing rings encircling the core and adapted to be compressed between said sleeves, devices to shift and secure the sleeves upon said core, one of said sleeves having an annular rib upon its inner periphery and being formed with oil ducts in its annular wall which are inclined downward from the upper edge of said rib, said oil ducts communicating with the openings in said core in all positions of adjustment of said sleeve.
- 25 4. In a piston, a hollow cylindrical core, bosses within the core adapted to receive a wrist pin, a plurality of peripheral sleeves slidable on said core, a resilient packing ring between adjacent ends of said sleeves, bolts secured in said bosses and nuts on said bolts coöperating with one of said sleeves to shift the same.
- 30 5. In a piston, a hollow cylindrical core, bosses within the core adapted to receive a wrist pin, a plurality of peripheral sleeves slidable on said core, a resilient packing ring between adjacent ends of said sleeves, bolts secured in said bosses and nuts on said bolts coöperating with one of said sleeves to shift the same.
- 35 6. In a piston, a hollow cylindrical core having a peripheral flange thereon, bosses within the core, a wrist-pin mounted at its ends in said bosses, a peripheral sleeve slidably mounted upon said core, a resilient packing ring between said flange and the adjacent end of said sleeve, a second peripheral sleeve slidably mounted at one end on said core, a second resilient packing ring between the adjacent ends of said sleeves, bolts secured in said bosses and passing through said wrist-pin and nuts on said bolts coöperating with said second sleeve to shift said sleeves and expand said rings radially.
- 40 7. In a piston, a hollow cylindrical core having openings in its annular wall between the ends thereof, a plurality of peripheral sleeves slidable on said core, resilient packing rings encircling the core and adapted to be compressed between said sleeves, devices to shift and secure the sleeves upon said core, one of said sleeves having an annular rib upon its inner periphery and being formed with oil ducts in its annular wall which are inclined downward from the upper edge of said rib, said oil ducts communicating with the openings in said core in all positions of adjustment of said sleeve.
- 45 8. In a piston, a hollow cylindrical core, bosses within the core adapted to receive a wrist pin, a plurality of peripheral sleeves slidable on said core, a resilient packing ring between adjacent ends of said sleeves, bolts secured in said bosses and nuts on said bolts coöperating with one of said sleeves to shift the same.
- 50 9. In a piston, a hollow cylindrical core, bosses within the core adapted to receive a wrist pin, a plurality of peripheral sleeves slidable on said core, a resilient packing ring between adjacent ends of said sleeves, bolts secured in said bosses and nuts on said bolts coöperating with one of said sleeves to shift the same.
- 55 10. In a piston, a hollow cylindrical core, bosses within the core adapted to receive a wrist pin, a plurality of peripheral sleeves slidable on said core, a resilient packing ring between adjacent ends of said sleeves, bolts secured in said bosses and nuts on said bolts coöperating with one of said sleeves to shift the same.
- 60 11. In a piston, a hollow cylindrical core, bosses within the core adapted to receive a wrist pin, a plurality of peripheral sleeves slidable on said core, a resilient packing ring between adjacent ends of said sleeves, bolts secured in said bosses and nuts on said bolts coöperating with one of said sleeves to shift the same.
- 65 12. In a piston, a hollow cylindrical core, bosses within the core adapted to receive a wrist pin, a plurality of peripheral sleeves slidable on said core, a resilient packing ring between adjacent ends of said sleeves, bolts secured in said bosses and nuts on said bolts coöperating with one of said sleeves to shift the same.
- 70 13. In a piston, a hollow cylindrical core, bosses within the core adapted to receive a wrist pin, a plurality of peripheral sleeves slidable on said core, a resilient packing ring between adjacent ends of said sleeves, bolts secured in said bosses and nuts on said bolts coöperating with one of said sleeves to shift the same.
- 75 14. In a piston, a hollow cylindrical core, bosses within the core adapted to receive a wrist pin, a plurality of peripheral sleeves slidable on said core, a resilient packing ring between adjacent ends of said sleeves, bolts secured in said bosses and nuts on said bolts coöperating with one of said sleeves to shift the same.

Whereof, I have hereunto subscribed my name to this specification.

FERDINAND G. HAAS.
